UNITED STATES PATENT OFFICE

BENJAMIN T. BALTHAZOR, OF RACINE, WISCONSIN

AIR SUPPLY DEVICE

Application filed February 10, 1930. Serial No. 427,282.

This invention relates to improvements in air supply devices and more particularly to devices of this character for use by a fireman.

An important object of the invention is to provide, in a manner as hereinafter set forth, an air supply device of the aforementioned character which is adapted to be embodied in or associated with the nozzle of a fire hose in a manner to collect fresh air from the stream of water discharging therefrom and the invention further contemplates means for conducting said fresh air from the nozzle to a fireman's mouth and nose to enable him to work in a smoke or gas filled building or enclosure without danger of being suffocated.

Another important object of the invention is to provide an air supply device for firemen of the aforementioned character which embodies means for preventing the entrance of smoke thereinto with the fresh air, said means comprising a rotatable band mounted adjacent the discharge end of the nozzle and adapted to be driven by the stream of water passing therethrough.

Other objects of the invention are to provide an air supply device of the character described which will be simple in construction, strong, durable, efficient in its use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view showing a device constructed in accordance with this invention in use.

Figure 2 is a view in elevation showing the discharge end of a fire hose with a nozzle thereon embodying the air supply device constituting this invention.

Figure 3 is a longitudinal vertical sectional view through the device.

Figure 4 is a vertical cross sectional view taken substantially on the line 4-4 of Fig-

ure 3 looking in the direction of the arrows.

Figure 5 is a detail view in elevation showing the rotatable fan adapted to prevent the entrance of smoke into the device.

Referring to the drawings in detail, the reference character 1 designates the end portion of a fire hose to which is connected the elongated pipe or handle 2 having its forward end threaded into the enlarged internally threaded end portion 3 of a substantially cylindrical discharge nozzle 4, the bore of which is of uniform diameter throughout.

A sleeve 5 encircles the nozzle 4 in spaced relation thereto and has one end connected thereto through the medium of the enlarged end portion 3, as clearly illustrated in Figure 3. The sleeve 5 is provided with an enlarged end portion 6 which projects forwardly beyond the corresponding end of the nozzle 4. The forward ends of the nozzle 4 and sleeve 5 are maintained in spaced concentric relation with respect to each other through the medium of the integral external flange 7 on the nozzle 4 which fits snugly within an internal flange 8 on the sleeve 5. The peripheries of the flanges 7 and 8 are provided with pairs of complementary, opposed spaced semi-circular recesses or notches which provide a series of openings 9 which extend transversely through the wall formed by said flanges 7 and 8.

A ring 10 of greater diameter than the nozzle 4 is mounted on said nozzle at its forward end and projects forwardly therefrom through the medium of an inturned flange portion 11 which encircles said nozzle and is fixed thereto in any suitable manner. The ring 10 is disposed within the enlarged end portion 6 of the sleeve 5 and is provided with integral, outwardly extending lugs 12 for engagement with the inner side of said enlarged portion 6. An annulus 13 is mounted for rotation in the ring 10 and is disposed in alignment with the bore of the nozzle 4 and said annulus is substantially of the same diameter as said nozzle.

Anti-friction balls 14 are disposed be-

tween the ring 10 and the annulus 13, said ring and annulus having their opposed sides provided with circumferentially extending grooves or channels to accommodate the balls. The inner periphery of the annulus 13 is provided with spiral ribs 15 (see Figures 3 and 4) and a fan 16 is fixed by any suitable means on the forward end of said annulus 13.

10 A longitudinally extending nipple 17 is fixed on the forward end of the enlarged portion 6 of the sleeve 5 and the bore of said nipple is of slightly greater size than the bore of the nozzle 4 and the annulus 13. 15 By thus making the bore of the nipple 17 slightly greater than that of the nozzle 4, an air space 18 is provided between the stream 19 and the inner wall of said nipple, as clearly seen in Figure 3 of the drawings. 20 Rearwardly of the flange 8, the sleeve 5 is provided with an integral externally threaded branch 20 for connection with a coupling 21 (see Figure 4) to which is connected a plurality of air conducting tubes 22 which have their free ends provided 25 with hoods 23 adapted to be secured tightly over the nose and mouth of the person using the device. If desired, the hoods 23 may also include a mask to go over the eyes of 30 the user.

The fan 16 is formed of a flat metallic ring having portions thereof struck out and bent forwardly therefrom at an appropriate angle to provide impeller blades 16', 35 as illustrated to advantage in Figure 5 of the drawings.

In use, the hoods 23 are positioned over the nose and mouth of the user in the manner illustrated to advantage in Figure 1 40 of the drawings. The stream of water 19 passing through the nozzle 4 and the annulus 13 engages with the spiral rib 15 on said annulus and rotates the same at great speed together with the fan 16 which is fixed 45 thereon. The normal tendency of the fan 16 is to blow air outwardly through the space 18 between the stream 19 and the nipple 17 and thus prevent the entrance of smoke into the chamber 23 formed between the nozzle 50 4 and the sleeve 5. However, when the user of the device inhales, the force of the band is overcome and fresh air may be drawn rearwardly past the fan 16, through the 55 openings 9 into the chamber 23 and then through the branch 20 into the air conducting tubes 22 to the hoods 23. The hood 23 may be of any desired type provided with 60 means by which the wearer may exhale without interfering with the fresh air to be inhaled. The fresh air thus inhaled is taken from the stream of water 19 passing through the hose as it is well known that such stream contains a certain amount of 65 fresh air and a portion of the air is also drawn rearwardly through the nipple 17

from the area immediately adjacent the outlet end thereof as indicated substantially by dotted lines in Figure 3 of the drawings. It is also well known that the immediate vicinity of the discharge end of a nozzle from which a stream of water is being discharged 70 on the pressure.

It is believed that the many advantages of an air supply device constructed in accordance with this invention will be readily understood, and although the preferred embodiment of the invention is as illustrated and described, it is to be understood that changes in the details of construction may be had which will fall within the scope of 75 the invention as claimed.

What is claimed is:—

1. In an air supply device of the character described, a nozzle, a sleeve encircling the nozzle in spaced relation thereto in a manner to provide an air chamber therebetween, said chamber open at its forward end, a rotary fan associated with the open end of the chamber in a manner to normally blow air therefrom, and suction tubes communicating with the chamber rearwardly of the fan and adapted to draw air therefrom. 80

2. In an air supply device of the character described, a nozzle, a sleeve encircling the nozzle in spaced relation thereto in a manner to provide an air chamber therebetween, said air chamber open at its forward end, a ring mounted on the nozzle and extending forwardly therefrom and disposed within the sleeve, an annulus mounted for rotation 90

within the ring, said annulus being substantially longitudinally aligned with the nozzle adjacent the discharge end thereof and having means thereon engageable with the water discharged from the nozzle for rotating said annulus, a fan fixed on the annulus for rotation therewith and adapted to normally blow air away from the chamber, and suction tubes connecting with the chamber rearwardly of the rotary fan to 100 draw air from said chamber. 105

3. In an air supply device of the character described, a discharge nozzle, a sleeve encircling the nozzle in spaced relation thereto in a manner to provide an air chamber therebetween and having an air outlet therein, said sleeve extending forwardly of the discharge end of the nozzle and a fan mounted for rotation on the discharge end portion of the nozzle and disposed within the sleeve. 110

4. In an air supply device of the character described, a water discharge nozzle, a sleeve encircling the nozzle in spaced relation thereto in a manner to provide an air chamber therebetween and having an air outlet therein, said sleeve having an enlarged end portion extending forwardly of the discharge end of the nozzle and co-axially therewith, a nipple mounted on the forward 125 130

end of the enlarged portion of the sleeve and having a longitudinal bore of greater diameter than the bore of the nozzle, said nipple and the nozzle being longitudinally aligned and a rotatable fan mounted on the nozzle and disposed for rotation in the enlarged end portion of the sleeve and adapted to normally eject air from said sleeve outwardly through the nipple.

10 5. In an air supply device of the character described, a water discharge nozzle, a sleeve encircling the nozzle in spaced relation thereto in a manner to provide an air chamber therebetween, said sleeve having an enlarged end portion projecting forwardly of the discharge end of the nozzle and coaxially with said nozzle, a ring mounted on the discharge end portion of the nozzle and extending outwardly and forwardly therefrom and disposed in the enlarged end portion of the sleeve, a water actuated annulus mounted for rotation within the ring in longitudinal alignment with the nozzle and adjacent the discharge end thereof, a fan 20 fixed on the forward end of the annulus for rotation therewith and disposed in the enlarged end portion of the sleeve, a nipple rigidly mounted on the forward end of the enlarged sleeve portion having a bore of slightly greater diameter than the bore of the nozzle and disposed in longitudinal alignment therewith, said sleeve adapted for the passage of the water from the nozzle in a manner to provide an air 30 space between the water passing therethrough and the inner periphery of said nipple, said fan being adapted to normally eject air from the chamber outwardly through the nipple and suction tubes communicating with the chamber rearwardly of the fan and adapted to withdraw air from said chamber.

In testimony whereof I affix my signature.
BENJAMIN T. BALTHAZOR.
